UNITED STATES PATENT OFFICE.

HARRY JAFFE, OF CHICAGO, ILLINOIS, ASSIGNOR, BY MESNE ASSIGNMENTS, TO
McCORD RADIATOR & MFG. CO., OF DETROIT, MICHIGAN, A CORPORATION OF
MAINE.

RADIATOR.

Application filed December 31, 1920. Serial No. 434,235.

To all whom it may concern:

Be it known that I, HARRY JAFFE, a citizen of the United States, and a resident of Chicago, in the county of Cook and State of Illinois, have invented certain new and useful Improvements in a Radiator, of which the following is a specification.

My invention relates to improvements in radiators for the water cooling systems of automobiles. The object of my invention is to provide a radiator which shall be more easily and cheaply constructed than heretofore; and which shall be lighter in weight and of equal or greater water cooling capacity.

A further object of my invention is to provide a construction whereby the quantity of sheet metal used in a radiator of specified dimensions is greatly reduced; in which the parts are more durable; in which the assembly of parts and the manufacture is easier; in which the construction generally is simplified and improved; and which shall reduce the quantity of water required.

My invention will be more readily understood by reference to the accompanying drawings forming part of this specification and in which:—

Figure 1 is a fragmentary front elevation of an automobile radiator made in accordance with my invention;

Figure 2 is an enlarged fragmentary front elevation showing in more detail the construction of the radiator;

Figure 3 is a vertical transverse sectional view of the radiator, particularly showing the parallel vertical water passages and the intermediate air passages and their construction;

Figure 4 is a fragmentary side elevation of one of the side walls of the water passages;

Figure 5 is a fragmentary perspective view of said side wall;

Figure 6 is a fragmentary side elevation of one of the folded intermediate spacer strips with which the air passages are produced;

Figure 7 is a fragmentary perspective view of the strip shown in Figure 6;

Figure 8 is a horizontal sectional view on the line 8—8 of Figure 3;

Figure 9 is an end elevation of the spacer strip shown in Figure 7;

Figure 10 is a fragmentary perspective view of an intermediate division strip; and

Figure 11 is a similar view of a modified form of the strip shown in Figure 10.

My improved radiator is of the honeycomb type being provided with hexagonal shaped nested air passages 1 extending through from the front to the back of the radiator and provided with vertically extending water passages 2 through which the water to be cooled falls from the top section 4 to the bottom section 3. The water passages 2 are quite narrow transversely and are zig-zagged vertically to reduce the speed of flowing water therethrough and the hexagonal air passages are built up or made of strips of quite thin sheet metal bent and formed to nest together to produce the nested hexagonal openings best shown in Figure 1.

Instead of arranging a singlefolded spacer strip between adjacent water passages, as illustrated in my United States Patent No. 1,310,416, I spread the water passages apart far enough to provide twin rows of air passages between adjacent vertical water passages and in a given dimension transversely of radiator surface, I reduce the quantity of metal used by quite a large percentage, thus reducing the cost of the material of which the radiator is made and proportionately reducing the labor cost.

In my former construction between each vertical row of hexagonal cells I provided a double walled water passage. In the present construction in the place of each alternate water passage I provide a single thickness division strip which is a simple zig-zag strip such as is illustrated in Figure 10, or in slightly modified form in Figure 11; in other words in my present improved construction I eliminate one vertical strip in each $\frac{3}{4}$ " transverse width of the radiator.

In my improved construction, while the elimination of each alternate water passage reduces the area of passages through which the water can flow vertically through the radiator, I find that the additional air contacting surfaces which I provide for the

water passages is sufficient to increase the radiating capacity and maintain equally good results in the cooling capacity of the radiator of equal dimensions with the form 5 shown in my said patent.

In building up my improved radiator I take a strip of sheet metal which is wide enough to extend from the front to the rear face of the radiator and I corrugate 10 or bend this sheet back and forth transversely to form V-shaped corrugations as shown at 6 in Figures 4 and 5, offsetting the edges of the apexes 7 at their ends as shown at 8 to contact with the intermediate 15 apexes 8 of an adjacent strip 5, to close the lateral edges of the water passages 2 as best shown in Figure 8.

These strips 5 are made continuous and in building the radiator I usually make a 20 strip 5 continuous from the lower end of one water passage to the lower end of the adjacent water passage, as best shown in Figure 3, wherein the strip 5 is shown as extending on an incline from the inner side 25 of one side of one water passage to the adjacent side of the next adjacent water passage, the incline being sufficient to bring the alternate apexes of the corrugations of the strips 5 into horizontal alignment and 30 thus begin the production of the nested parallel rows of hexagonal air passages between the two adjacent vertical water passages.

Having bent a strip 5 back upon itself 35 as best shown in Figure 3, to produce the adjacent sides of two adjacent water passages, I next proceed to bend other strips to be assembled therewith to complete the water passages and complete the adjacent 40 portions of the radiator. To properly space the adjacent side walls of adjacent water passages, which I will now designate as 9 and 10 (see Figure 3) I provide two forms of filler or spacer strips, one of these 45 strips being shown in Figures 6, 7 and 9. This spacer strip 11 is produced out of a strip of thin sheet metal of a width to reach from the front to the rear face of the radiator and is bent transversely to provide 50 horizontal division walls 12 to form the top and bottom walls of the hexagonal air passages 1 and to provide V-shaped walls 13 projecting outwardly from the horizontal walls 12 in opposite directions 55 between adjacent walls 12 as best shown in Figure 7, and adapted to fit into the V-shaped grooves in the sides of the adjacent water passages, that is, against the walls 9 and 10, as best shown in Figure 3. Before 60 bending the strips 11 into the form shown in Figure 7 I make incisions or cuts 13 in the strip, parallel with the side edges thereof and approximately one third of the width of the strip from each edge and extending from edge to edge of the adjacent 65

parts of the strip which produce the horizontal walls 12. These cuts produce a portion 14 of the strip which is free at its transverse ends and is still joined to the strip at its edges as best shown in Figure 7, and in forming the strip 11 into the shape illustrated in Figure 7 I form the part 14 inwardly instead of outwardly as illustrated at 15 and as best shown in Figure 9. These inwardly projecting parts 14 provide intermediate walls 16 in the air passages which tend to divide and cut up the air streams flowing through the hexagonal air passages and force them into close contact with the sides of the water passages, which are in a sense uncovered by the inwardly projecting parts 14.

In building up my radiator I make use of two of the strips 11 between each pair of vertical water passages, as best illustrated 85 in Figure 3 and I provide an intermediate division wall 17 with which the opposed sides of these two spacer strips are adapted to contact, which wall 17 is arranged midway between adjacent water passages. 90

In producing the wall 17 I take a strip of sheet metal of a width equal to the other strips and I form it into a V-shaped corrugated sheet by corrugations 18 running transversely thereof, as best shown in Figure 10, 95 and of a size to nest with the spacer strips and cause them to produce the hexagonal openings shown in Figure 1. This thin division strip is very easily and cheaply produced and as far as the spacer strips 11 are 100 concerned, takes the place of a water passage in causing the corrugations of the spacer strips to properly register and produce the regular hexagonal holes or air passages desired.

For the purpose of reducing the weight of the radiator I provide deep V-notches 19 in the edges of the spacer strips 11 which are so arranged that when the strip is folded up the V-walls 14 are cut away at their ends 110 at best shown in Figure 11, and I thus avoid the necessity of causing these walls to closely contact with the inwardly inclined ends 8 of the side walls of the water passages.

It is well understood that in the building 115 of such radiators as the one to which my invention appertains, the various strips are arranged together in nested form as shown in Figure 1, and then the whole body of the radiator is clamped transversely tightly together and in such clamped condition the front and the rear surfaces of the radiator is dipped into melted solder to close the transverse ends of the water passages and solidify the various strips into a unitary 120 whole. It is also understood that where two sheets of metal are in contact at the point where they are soldered, the solder not only enters in between the two sheets, but also coats the outer surfaces thereof, and that 125 130

the larger percentage of joints there are which are presented to take up solder, the greater the percentage of solder which is absorbed in the joints and on the edges of the sheets.

By the elimination of the intermediate water passage in the construction of my novel radiator and the introduction in the place thereof of a single corrugated division sheet, I have greatly reduced the quantity of solder which is necessary for the production of the radiator.

Another feature which reduces the quantity of solder is the large V-shaped notches 18 which I provide in the edges of this sheet and the edges of the sides of the water passage and the edges of the division sheet 17.

For the purpose of causing the spacer strips 5 to more readily and definitely register with the divisional strip 17 I sometimes produce shallow grooves 20, see Figure 11, in the apexes of the corrugations of the division strip to receive the slim sharp ends 21 formed on the edges of the spacer strips 25 between the deep notches 19.

As it is obvious that many details of construction can be changed or modified without departing from my invention, I do not limit or confine my invention to the specific

details of construction herein shown and described.

I claim:

In a radiator of the kind described, thin walled vertical corrugated water passages, the water passages spaced apart by two substantially similar spaced strips and an intermediate divisional strip, the spacer strips formed to provide horizontal top and bottom walls for hexagonal air passages, the alternate vertical connecting walls deflected to nest with the water walls and the other connecting walls deflected to nest with the divisional strip, the opposed apexes of the two spacer strips spaced apart vertically midway of each other, the divisional strip formed to cooperate with the spacer strips to complete two vertical lines of hexagonal air passages between each two water passages and arranged to extend diagonally from the apexes of one spacer strip to the apexes of the opposed spacer strip, the apexes of the divisional strip being grooved to receive the edges of the apexes of the spacer strips to retain said parts in their relative positions.

Signed at Chicago, Illinois, this 24th day of December, 1920.

HARRY JAFFE.
